COAT HANGER

Filed Nov. 3, 1931

INVENTOR.
JAMES MALLEY,
BY
Louis Necho
ATTORNEY.

UNITED STATES PATENT OFFICE

JAMES MALLEY, OF RICHMOND, VIRGINIA

COAT HANGER

Application filed November 3, 1931. Serial No. 572,754.

My invention relates to a new and useful coat hanger and it relates more particularly to a coat hanger which is provided with pockets adapted to receive cakes or blocks of a moth killing preparation to insure perfect protection of garments on said hangers or on ordinary hangers positioned in the same closet.

The fumes or vapors formed from the anti-moth cake are heavier than ordinary atmosphere and flow downwardly within the closet which makes it necessary that the anti-moth cake be positioned at the top or near the upper end of the garment, so that the moth killing fumes may seep down through the body and folds of the garment.

Anti-moth substances used in the powdered form are not desirable nor effective and if the anti-moth substance is in the form of a cake positioned in the bottom of the closet or on shelves in the closet or in the pockets of garments it is not so efficient as it might be, as is well known.

Other expedients have been resorted to employing the broad idea of positioning the anti-moth substance within or in proximity to the coat hanger, but it is the object of my invention to provide a novel construction which is highly efficient and which will be inexpensive to produce.

The nature of my invention and its advantages will be more clearly understood from the following specification read in connection with the accompanying drawing in which:

Figure 1 represents a perspective view of a hanger embodying my invention.

Figure 2 represents a section on line 2—2 of Figure 1.

Figure 3 represents a perspective view of the anti-moth cake shown detached.

Figure 4 represents a sectional view showing a modified form of my invention.

Figure 5 is a perspective view showing a further modified form of my invention.

Referring to the drawing in which like reference characters indicate like parts, 1 designates a coat hanger of any suitable construction with or without the cross bar 2. 3 designates a hook for supporting the hanger. In

the body of the hanger are formed the apertures or cut out portions 4 which are suitably spaced and of which any number can be provided, 5 designates a cake or block formed of any slowly evaporating substance the fumes of which will kill moths and which is of a size to fit within the apertures 4. In the body of the cake 5 and near the bottom thereof is embedded a strap 6 of a flexible material the free ends 7 of which can be deflected downwardly about the bottom edge of the hanger 1 to hold the cake 5 within the aperture 4, pending evaporation of the cake. When the cake 5 has evaporated a refill cake similar to that shown in Figure 3 is placed in the aperture 4, so that the hanger is at all times charged or supplied with the moth killing substance. If desired two flexible straps 6 positioned near the ends of the cake may be used as shown in Figure 4.

In Figure 5, I have shown a modified form in which a plate 8 of cardboard or other material is embedded in the cake 5 and the strap 6 is either formed integrally with or suitably secured to the plate 8. This construction is somewhat stronger and may be used if desired.

Having thus described my invention, what I claim as new and desire to secure by Letters Patent is:

A coat hanger comprising a garment supporting member having cut-out portions therein, cakes of moth-killing volatile substance positioned in said cut-out portions, and fastening straps embedded in and projecting beyond the edges of said cakes, said straps being made of flexible material whereby the ends thereof may be twisted around said garment supporting member to secure said cakes within said cut-out portions.

In testimony whereof I affix my signature.

JAMES MALLEY.
